UNITED STATES PATENT OFFICE.

CARL BARUS, OF WASHINGTON, DISTRICT OF COLUMBIA, ASSIGNOR OF ONE-HALF TO ALBERT LIEBER, OF INDIANAPOLIS, INDIANA.

APPARATUS FOR RACKING OR TRANSFERRING CARBONIZED LIQUIDS.

SPECIFICATION forming part of Letters Patent No. 548,502, dated October 22, 1895.

Application filed December 20, 1894. Serial No. 532,493. (No model.)

To all whom it may concern:

Be it known that I, CARL BARUS, of Washington, in the District of Columbia, have invented certain new and useful Improvements 5 in Apparatus for Racking or Transferring Carbonized Liquids, of which the following is a specification, reference being had to the accompanying drawings.

The object of my invention is the production of means whereby liquids charged with gas—as, for instance, carbonized beer—may be transferred from one receptacle to another without appreciable waste of liquid or gas, and whereby the receiving-receptacle may be 15 hermetically sealed without incidental waste.

To these ends my invention consists in the novel construction of a bung and socket and of a cock adapted to co-operate therewith to establish an equilibrium of the pressure of 20 gas within the two receptacles, without which the transfer of carbonized liquid is attended by decarbonization or frothing.

Referring to the drawings, in which I have illustrated the preferred form of my apparatus and several modifications of the construction of the bung, Figure I is a view illustrating the application of my device. Fig. II is a central longitudinal section through the cock and bung, showing the parts in the position they assume during the racking of the liquid. Fig. III is a similar view showing the cock closed. Fig. IV is a central longitudinal section through the bung, the cock being shown in elevation and the bung rotated to 35 seal the receiving-receptacle. Fig. V is an elevation showing the cock about to be forced into close relation to the bung, the position of the parts when the cock and bung are locked securely together being shown in dotted lines. Fig. VI is a sectional view of a 40 modification of my device, and Fig. VII is a view of another modification.

Referring to the figures on the drawings, 1 and 2 indicate closed receptacles—as, for instance, kegs—which, for convenient designation, I shall term a “discharging” and a “receiving” receptacle, respectively. These are 45 preferably placed in different horizontal planes, as illustrated, and it being understood that it is desired to transfer carbonized

or other gas-charged liquid from the upper to the lower receptacle, I will proceed to describe the special mechanism I employ for effecting the transfer.

3 and 4 indicate the top and bottom of the 55 receiving-receptacle, the former being provided with a preferably-circular aperture 5 for the reception of the correlative-shaped head 6 of a cylindrical socket 7, preferably of less diameter than the diameter of the head 60 and depending therefrom into the receptacle 2. The head is provided with an annular flange 8, let into the top 3 to insure a tight joint to prevent the escape of gas; but the expansion or swelling of the wooden receptacle 65 ordinarily suffices for this purpose. The internal walls of the socket preferably converge somewhat from the top to the restricted lower end 9, and are screw-threaded to receive a correlative-converging externally-threaded 70 hollow bung 10, closed at its lower end, as illustrated. The socket is provided with a gas-vent 11, preferably immediately below the head, and with somewhat larger ports 12 and 13, connected by a pipe 14, as illustrated. It will be 75 observed that the port 13 is directly below the port 12 and is also below the upper threaded portion of the socket and the bottom of the bung, this arrangement permitting the flow of liquid from the port 12, through the pipe 14, 80 and into the socket below the bung, for a purpose hereinafter specified, and finally through a depending tube 15, preferably screwed into an aperture 16 in the bottom of the socket and extending to the bottom of the receptacle. 85 In order to prevent clogging, the tube 16 may be cut away at an angle, as indicated at 17.

The hollow bung 10 is designed, as illustrated, to screw into the socket, and is provided, therefore, as before stated, with external threads, correlative with the internal threads of the socket, and with a lateral, preferably hexagonal, flange 18 at its top, adapted to limit its movement and to co-operate with bung-actuating mechanism presently to be described. The bung is also provided with a vent 19 and a port 20 properly located, respectively, to register with the vent 11 and the port 20 in the socket when the parts are in the position illustrated in Fig. I, the rota- 90 95 100

tion of the bung sealing the receptacle by removing the vents and ports in the socket and bung out of corelation.

In order to prevent the escape of gas between the threads of the socket and bung, I coat either or both of them with a film of soft metal 20°—as, for instance, tin or solder—so that when these ports are screwed together and the bung is closed the receptacle will be hermetically sealed.

21 indicates an annular bench surrounding the inner walls of the bung, adapted to receive a flexible washer 22.

23 indicates diametrically-opposite recesses 15 in the under side of the flange 18.

The mechanism thus far described constitutes what I will call the "sealing" mechanism, for the reason that these parts co-operate to hermetically seal the receptacle or to 20 permit of the egress of gas and the ingress of liquid, and are not designed to be detached from each other or from the receptacle except for cleaning or repairing. I shall now proceed, however, to describe the coupling mechanism, which is ordinarily connected with the 25 discharging receptacle or reservoir and which is only operatively connected with the sealing mechanism when it is desired to transfer liquid to the receiving-receptacle.

30 24 indicates what may be termed an "equalizing-cock," its office being to permit the escape of gas into the receiving-receptacle to initially establish an equilibrium between the 35 internal pressures of the two receptacles and to thereafter permit the ingress of liquid into the receiving-receptacle and the escape of gas therefrom into the reservoir, to maintain the equilibrium of pressure during the transfer of the liquid.

40 25 indicates the cock-casing, provided with a depending bung-tube 26 of a diameter corresponding with the internal diameter of the bung and adapted to fit closely therein, the annular flange 27 of the casing fitting within 45 the annular bench 21 and compressing the washer 22 to effect an air-tight connection between the cock and bung.

The cock-casing proper is provided with a tapering bore 28 for the reception of the 50 relatively-tapered plug 29 and with a bore 30 at right angles thereto, forming a continuation of the tube 26, and the upwardly-extending pipe connection 31, which connection is preferably screw-threaded to receive the end of a 55 preferably-flexible pipe 32, connected at its opposite end with the discharging-receptacle at or near its bottom. The plug is provided with a transverse aperture, as usual.

33 indicates a comparatively small pipe connection 60 screwed into the small end of the plug and connected with the interior of the receptacle 2 through curved ducts 34 and 35 in the plug and casing, respectively, and through a small metallic pipe 36, extending longitudinally through the tube 26 and communicating at its opposite ends with the duct 35 and with the aperture 37 through the side of the

tube 26, which aperture is correlative with the vent 17 in the bung. The duct 34 is provided with an elongated opening 34° for a 70 purpose hereinafter made apparent.

38 indicates a small tube screwed upon the connection 33 and communicating at its opposite end with the discharging-receptacle, above the liquid therein. 75

Suitable means may be employed for preventing leakage around the plug of the cock and to compensate for wear, the simple device illustrated consisting of a disk 39 of greater diameter than the end of the plug and secured thereto by screws 40, an intermediate resilient gasket 41 serving to constantly urge the plug into its socket and to constitute a packing. The plug is provided with a suitable handle 42, as usual. 80

The sealing and coupling mechanisms described constitute the apparatus especially designed to successfully accomplish the transfer of the liquid; but much time and labor can be saved by the employment of certain 90 novel mechanism for attaching or detaching the cock to or from the bung and for rotating the bung to open the same when the cock is so attached or to close and seal it when the transfer has been effected and before the cock 95 is removed. To this end I secure upon the cock-casing by any suitable means a semicylindrical saddle 43, provided upon its opposite sides with depending lugs 44 and apertured at its top for the reception of the pipe connection 31. Between the lugs 44 on either side of the saddle I pivot, as upon rods 45, swinging arms 46, bifurcated at either end, as indicated, for the reception of diametrically-opposite actuating-levers 47, pivotally mounted upon rods 48, and for gravity-pawls 49, pivoted upon the rods 45 and pointed at their lower ends to engage ratchet-teeth 50 upon the levers. The short ends of the levers are designed to engage the recesses 23 in the bung-head. 105

Springs 51 or other suitable mechanism may be employed to assist gravity in effecting the engagement of the pawls with the levers, and springs 52 may be secured at one end to the 115 saddle and detachably fastened to eyelets 53 upon the arms when it is desired to hold the pawls out of engagement with the levers—as, for instance, when removing the cock from the bung. 120

In the drawings I have illustrated, in addition to the preferred form of my device certain modifications thereof, Fig. VI illustrating as the equivalent of the part 4 a cylindrical connection entirely surrounding the lower 125 end of the socket, into which liquid passes through the ports 12 and 20 and to which the tube 15 is directly connected instead of to the socket.

Fig. VII shows a modification in which there 130 is no channel for the liquid external of the socket, the bung being provided with a valve end adapted to seat in the bottom of the socket, the liquid passing through ports im-

mediately above the valve and around the same within the socket.

Various modifications of the details of construction shown and described might be made to suit varying conditions, and I desire to reserve to myself the right to make such changes and modifications as may come within the scope of my invention.

The operation of my device is as follows: 10 Supposing the tubes 32 and 38 to be properly connected to the discharging-receptacle, the bung of the receiving-receptacle to be in the opened or unsealed position, and the cock to be closed, the levers are raised and the bung- 15 tube of the cock is inserted into the bung. The operator now grasps the handles of the levers and forces them downward, when, as is evident, the cock will be forced closely against and into engagement with the bung, 20 the levers being fulcrumed within the recesses in the bung-head. The parts are securely locked in place by the pawls dropping into engagement with the teeth upon the levers, the aperture 37 and the vent 19 being correlative. 25 The plug of the cock is now turned until communication is established between the two receptacles through the vents 11 and 19, the tube 36, the vents 35 and 34, and the tube 38, which, by virtue of the elongated 30 openings, will be somewhat in advance of the establishment of communication between the receptacles through the pipe 32, cock, bung, socket, and tube 17. It will appear then that the gas will flow from one receptacle to the 35 other until the pressure within the receptacles is equalized, when, in accordance with well-known principles, the liquid will flow freely, the gas displaced by the inflowing liquid escaping into the discharging-receptacle 40 to maintain the equality of pressure. The racking of the desired quantity of liquid having been accomplished the cock is closed and the operator swings the levers laterally, turning the bung sufficiently to remove the vents 45 and ports in the socket and bung out of correlation. By reason of the soft-metal seal between the threads of the bung and socket the receiving-receptacle is hermetically sealed. The cock is removed by forcing the levers 50 upward, their short arms being fulcrumed against the head of the socket and the pawls being held out of engagement with the teeth by the spring 52.

What I claim is—

55 1. The combination with a socket provided with a vent and port and a hollow bung likewise provided with a vent and port, of a cock having separate independent channels therethrough communicating, respectively, with the vent and port in the bung, substantially as specified.

2. The combination with a hollow socket provided with a vent and port, of a hollow bung within said socket provided with a vent 60 and port, and a cock provided with a plurality

of tubes adapted to communicate, respectively, with the vent and port in the bung, substantially as specified.

3. The combination with a receptacle, of a hollow socket provided with a vent and port, 70 a hollow bung within said socket provided with a vent and port, and a cock-tube adapted to fit within said bung, and a tube within said last named tube and communicating with an aperture therein, substantially as specified. 75

4. The combination with a receptacle, of a hollow socket provided with a vent and port, and a tube extending to the opposite end of the receptacle and communicating with said port, a hollow bung within said socket provided with a vent and port, and a cock provided with a plurality of tubes communicating, respectively, with the vent and port of the bung, substantially as specified. 80

5. The combination with a receptacle, of a 85 socket provided with a vent and a plurality of ports, a connecting pipe between two of the ports, a tube extending from the socket to the opposite end of the receptacle, and a hollow bung within the socket provided with a closed 90 end and with a vent and port, substantially as specified.

6. The combination with a receptacle, of a socket provided with a vent and a plurality of ports, a connecting pipe between the ports, 95 a tube extending from the socket to the opposite end of the receptacle, and a hollow bung within the socket provided with a closed end and with a vent and port, and a layer or coating of soft metal intermediate of the cock and bung, substantially as specified. 100

7. In a racking device the combination with a socket and bung, of a cock and actuating mechanism for forcing the cock into the bung and for actuating the latter, substantially as 105 specified.

8. In a racking device, the combination with a socket and bung, of a cock and actuating mechanism for forcing the cock into the bung and for actuating the cock, substantially as 110 specified.

9. The combination with a revoluble bung, of a cock provided with actuating levers engaging said bung whereby said levers may be actuated to secure the cock and bung together and to open and close the latter, substantially as specified. 115

10. The combination with a hollow socket provided with a vent and port, of a hollow bung within said socket provided with a vent 120 and port, and a cock provided with a plurality of tubes adapted to communicate, respectively, with the vent and port in the bung, and means for forcing the cock into operative relation with the bung, substantially as specified. 125

11. The combination with a revoluble hollow bung provided with a recessed head, of a cock provided with a depending tube and actuating levers adapted to engage the re- 130

cesses in the head and adapted to be actuated to force the tube into and to rotate the bung, substantially as specified.

12. The combination with a cock, of swinging arms supported thereby, actuating levers pivoted at the free extremities of the arms and pawl and ratchet mechanism adapted to lock the levers, substantially as specified.

13. The combination with a cock, of swinging arms operatively connected thereto, and levers fulcrumed at the free extremities of the said arms, substantially as specified.

14. The combination with a cock, swinging arms operatively connected thereto, and le-

vers fulcrumed upon the swinging arms, of a bung, and mechanism thereupon adapted to co-operate with the levers, substantially as specified.

15. The combination with a saddle, of swinging arms, carried thereby, and levers fulcrumed at the free extremities of the arms, substantially as specified.

In testimony of all which I have hereunto subscribed my name.

CARL BARUS.
